UNITED STATES PATENT OFFICE.

LOUIS SEIFERD, OF BROOKLYN, NEW YORK.

COLLAPSIBLE MOLD.

1,294,311.

Specification of Letters Patent. Patented Feb. 11, 1919.

Application filed March 26, 1918. Serial No. 224,833.

To all whom it may concern:

Be it known that I, LOUIS SEIFERD, a citizen of the United States of America, residing at Brooklyn, in the county of Kings and State of New York, have invented new and useful Improvements in Collapsible Molds, of which the following is a specification.

This invention relates in general to molds, and is a device of this character adapted for molding cement and concrete blocks to be used for building purposes.

Its principal object is to provide a device of this character in which the blocks can be molded in pairs, the individual blocks of each pair existing in spaced relation to each other, thereby providing a building block which, when used with other similar blocks, will make a wall which has an air space between its two faces.

A further object of the invention is to provide a mold for casting the aforesaid blocks, so that they may be adapted for use in straight walls and in corners.

A still further object is to provide a mold which may be completely collapsed when not in use.

A still further object of this invention is to provide a collapsible core for the mold which core fills the space which becomes the air space between the pair of finished blocks.

A still further object is to provide a device of the kind mentioned which is simple in construction, durable and effective in operation and inexpensive to manufacture.

Still further and other objects will appear as the invention is set forth in detail in the following description.

The drawings illustrate and the specification describes a particular embodiment of the invention but to this embodiment it is not to be restricted. Continued use in practice may make manifest certain desirable changes or alterations and the right is claimed to make any which do not deviate from the scope of the subjoined claims.

The same numerals of reference designate the same parts throughout the several figures of the drawings, wherein:

Figure 1 is a plan view,

Fig. 2 is an end view,

Fig. 3 is a section on the line 3—3 of Fig. 1,

Fig. 4 is a section on the line 4—4 of Fig. 1,

Fig. 5 is a collective perspective of a section of the collapsible core, 55

Fig. 6 is a perspective view of a block cast for straight walls,

Fig. 7 is a perspective view of a block cast for corners, 60

Fig. 8 is a perspective view of a section of a solid core,

Fig. 9 is a perspective view of the plate used for filling such of the dove-tail slots as are not in use, 65

Referring to the drawings, the mold is shown as comprising a base plate 1 with the upstanding side walls 2 and 3 and the end walls 4. The several walls stand upwardly from the base plate and surround the latter on its perimeters. The side walls 2 and 3 have formed on their inner face and adjacent their ends, V-shaped depressions 5, the two depressions on opposite walls coöperating to form substantially a 70 V-slot. The ends of the end walls are beveled to conform to these V-shaped depressions so that the end walls may be connected each with two opposite side walls by having their beveled ends engage the V- 75 shaped depressions.

As a means for securing the side and end walls together, there are provided hasps 6 which are hingedly attached to the side walls adjacent their ends and swing around in front of the end walls, the latter being provided with fastening devices 7 which engage the hasps and lock them to the end walls after they have been brought into contact with the latter. 80

The base plate 1 may be omitted, if there is a suitable level surface on which to assemble the several walls, but if there is not, the use of the base plate is essential, so that there may be a level base on which to cast the blocks, for which this invention is designed. 85

Positioned within the walls just referred to, there is a core block which operates as the spacing medium between the blocks formed in the mold. This core block comprises two plates 8 which are wedged-shape in cross section and which are formed in sections that are interconnected by means of 90

pins 25, the pins being fixed in one section and detachably engaging the connection section in the holes 26 formed therein. On the thinner longitudinal edges of each of the plates 8, there are provided the eye-members 9. The two plates are adapted for attachment to each other and when they are in use as a spacing member between the blocks being cast, the plug members 10 are employed. These plug members are wedged-shaped, both in thickness and in plan and on their wider longitudinal edges are provided with eye-members 11.

The plug members 10 are designed for insertion between the plates 8 and their eye-members 11 are so positioned that they align with the eye-members 9 just referred to. Thus the several eye-members 9 and the eye-members 11, when the plug members are inserted between the plates 8, provide for the assembling of the plates and plug members by means of a rod member 12 which passes through the eye-members and which at one end is provided with a right-angled bend 13, by which it may be inserted and withdrawn from the eye-members.

The two plates are so proportioned that, when the plug members 10 are between them and their thicker longitudinal edges are together, the distance between the outer faces of the two at their thicker edges is the same as the distance between the outer faces of the two at their thinner edges. Thus when the plug members 10 are withdrawn, the core may be collapsed by bringing together the thinner edges of the two plates 8.

On the inner faces of the end walls 4 and medially disposed between the beveled edges thereof, there are formed dove-tail slots 16. The core plate is designed to be attached to the end walls by means of this dove-tail slot and for this purpose, the dove-tail tenons 15 are formed at the free ends of the core plate. These tenons correspond in cross section to the cross section of the dove-tail slots.

The core plate as a whole comprises two sections, one of which is about one-fourth of the length of the other and the two sections are interconnected by a double dove-tail bar 17, which engages corresponding dove-tail slots 14 formed on the interconnecting ends of the two sections. The length of this bar is substantially the same as the height of the walls of the mold, the core plate when in position being also of the same height as the mold.

The side wall 3 is provided with a dove-tail slot 18 which is identical with the dove-tail slot 16 and one of the plates of the smaller section of the core plate is provided with a dove-tail slot 19. The slots 19 and 18 are provided so that the smaller section of the core plate may be detached

from the larger section and the end of the smaller section made to engage the slot 18 and the bar 17 made to engage the slot 19 and the slot in the end of the larger section. This provision of making the core plate in two sections so as to shift the position of the smaller section is for the purpose of casting the straight block and the end block shown in Figs. 6 and 7 respectively.

In the construction of the core, the manner of attaching its several parts is the same in both sections, each section being identical with the other except in the matter of length.

In Fig. 9, there is shown a plate 30 to be used for filling the dove-tail slot 16 on one of the end walls, or the dove-tail slot 18 in the side wall 3, this plate, of course, filling the slot to which the core is not connected. The plate 30 is provided with a handle member 31 to permit its being withdrawn from the slot in which it is inserted.

Both the larger and the smaller sections of the core member are provided with transverse recesses 20 formed in those sections of the plates 8 which carry the pins 25. These recesses 20 are provided for the purpose of receiving the tie rods 21, so that the latter may be held in their proper relative position while the cement or concrete is being cast around them.

In Fig. 6, there is shown a spaced block comprising two cement or concrete units (the two interconnected units being considered one block). In casting such a block, the core is attached between the two end walls 4 and the two sections of the former are interconnected at their ends. The mold is then filled on both sides of the core. After the material is set, the side walls are dropped down out of position by disconnecting the hasps 6 from the end walls. The rod member 12 is then withdrawn, leaving the plug members 10 loose to be disconnected from between the two plates 8. The end walls are then removed by disengaging the dove-tail slots 16 from the dove-tail tenons 15.

The two plates 8 may then be loosened from the block by pressing their thinner upper edges toward each other, the two sections of the core having first been separated by the withdrawal of the double dove-tail bar 17 to permit the upper edges of the plate 8 to be pressed toward each other. The core is thereafter separated from the casting block by withdrawing those sections of the plates 8 which contain the pins 25, these sections being withdrawn longitudinally from the casting block. After having done this, those sections of the plates 8 containing the holes 26 are withdrawn vertically from the casting block.

In Fig. 7, there is shown a block adapted for corner work. In casting this block, the

core is arranged so that the tenon 15 of its shorter section engages the dove-tail slot 18 and this section is connected with the longer section by having the bar 17 engage 5 the dove-tail slot 19 and the slot 14 in the end of the longer section. The core when arranged in this manner is substantially L-shape in plan and the pouring of the material in the mold between the walls thereof 10 and the core results in the formation of a block like that shown in Fig. 7, consisting of an L-shape cement block 23 and a shorter block 24, the latter being interconnected with the former by the tie rods 21, and this 15 latter block standing in spaced relation to both lugs of the L-shape block.

It will be observed that the block shown in Fig. 6 is adapted for use on straight walls, while that shown in Fig. 7 is adapted for 20 use in corner work, thus walls may be built by the employment of said blocks, so that an air space will intervene between the inner and outer faces of the walls. Each air space will serve to effectively preclude dampness.

It will be further observed that the particular arrangement of the core into sections, capable of being assembled longitudinally provides for the casting of the straight blocks shown in Fig. 6 in batteries, so that 25 a whole layer of blocks may, in the building of a wall, be cast with one setting of a multiple of the cores assembled longitudinally, it being only necessary in such an employment of the invention to omit the end wall 4 where one of the molds connects with an adjacent mold and to provide for the interconnection of the cores in the manner in which the sections of the two plates 8 are 30 interconnected, such as by pins 25 and holes 26.

In Fig. 8 there is shown a solid core 27, divided longitudinally into sections which interconnect by pins 25 held in one section which engage holes 26 formed in the other 45 section, this manner of connection being identical with the manner of connecting the two sections of the plates 8. That section of the core 27 which carries the pins 25 is, as is the collapsible core, provided with transverse recesses 20 adapted for holding the tie rods 21.

The core 27 has a dove-tail tenon 29 for engagement with one of the dove-tail slots 16 and carries on its opposite ends, a dove-tail slot 26 for engagement with the double 55 dove-tail bar 17.

This solid core 27 is adapted for use in place of the collapsible core, when it is so desired.

The invention having been described, what is claimed as new and useful is:

1. A mold of the character described comprising side and end walls and a sectional core plate having certain of its sections de-

signed for connection in alinement with or 65 at an angle to the remaining sections, the core plate connecting with certain walls of the mold, whereby there may be cast building blocks consisting of units standing in spaced relation to each other. 70

2. A mold of the character described comprising side and end walls detachably connected together, and a sectional core plate certain of whose sections may be connected either in alinement with or at an angle to 75 the remaining sections, the core plate being connected with the two end walls when its sections are in alinement and connected to an end wall and a side wall when its sections are at an angle to each other, whereby there 80 may be cast, so that they stand in spaced relation to each other, building blocks adapted for straight walls and for corners.

3. A mold of the character described comprising side walls, end walls detachably connected to the side walls, the end walls and one side wall having dove-tail slots formed on their inner faces, a core plate composed of two sections, so that the core plate may be connected between the two end walls, 85 either section having a dove-tail tenon for engaging a dove-tail slot, and means for connecting the two sections of the core plate together. 90

4. A mold of the character described comprising side walls, end walls detachably connected to the side walls, the end walls having beveled side edges, the side walls having V-shape depressions at their ends, hasps 100 hingedly connected on the side walls, devices on the end walls for connecting with the hasps, and a detachable core having means for connecting with certain of the walls. 95

5. A mold of the character described comprising side walls, end walls detachably connected to the side walls, the two end walls and one side wall having dove-tail slots formed therein, a sectional core plate comprising one relatively long section having a dove-tail slot in its end and a short section also having a dove-tail slot in its end and a dove-tail slot on one side, and a double dove-tail bar for interconnecting the two sections of the core, whereby the smaller 110 section may be placed in alinement with or at right angles with the longer section, the free ends of the two sections being provided with dove-tail tenons for engagement with the dove-tail slots of the side and end walls. 115

6. A core comprising two plates wedged-shape in cross section, eye-members secured to each of the plates on their thinner longitudinal edges, core plugs tapering in thickness and designed for insertion between the wedged-shape plates at their thinner edges, eye-members attached to the thicker edges of the core plugs and so positioned as to 120 125

aline with the aforesaid eye-members, and a rod member slidably engaging all of said eye-members.

7. A core comprising a multiple of sections detachably connected end to end, each section consisting of two plates wedged-shape in cross section, core plugs tapering

in thickness and designed for insertion between the wedged-shape plates at their thinner edges, and means for connecting the 10 wedged-shape plates and the core plugs together.

In testimony whereof I affix my signature.

LOUIS SEIFERD.
